EDUCATIONAL GAME BOARD

Angelo F. Nucci, 1667 Crestwood Road,
Toledo, Ohio 43612

Filed Feb. 13, 1969, Ser. No. 15,768

Term of patent 14 years

Int. Cl. D21—01
U.S. Cl. D34—5

I claim:

The ornamental design for an educational game board, as shown and described.
